UNITED STATES PATENT OFFICE

99,937

DESIGN FOR A TEXTILE FABRIC OR SIMILAR ARTICLE OF MANUFACTURE

John F. Gaul, Jr., Clifton, N. J., assignor, by mesne assignments, to Reconstruction Finance Corporation, a corporation of the United States

Application June 20, 1935, Serial No. 57,361

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, in which Fig. 1 shows a face view of a piece of textile fabric embodying my design, while Fig. 2 is a cross section thereof.

The characteristic feature of the present design resides in series of parallel bars or ridges of substantially semi-circular cross section and

spaced apart a distance equal to substantially the width of the bars or ridges arranged on a base fabric having a substantially plain surface and extending over the face of the entire fabric, said ridges having thereon series of closely arranged parallel diagonal lines, the portions of the face of the base fabric intermediate said ridges having criss-cross lines thereon which are parallel and perpendicular to the edges of said ridges.

I claim:

The ornamental design for a textile fabric or similar article of manufacture, substantially as shown and described.

JOHN F. GAUL, JR.
